UNITED STATES PATENT OFFICE

152,152

DESIGN FOR AN AIRPLANE TOY

Andrew Halvas, Astoria, N. Y.

Application August 2, 1946, Serial No. 132,243

Term of patent 3½ years

(Cl. D34—15)

To all whom it may concern:

Be it known that I, Andrew Halvas, a citizen of the United States, residing in Astoria, State of New York, have invented a new, original, and ornamental Design for an Airplane Toy, of which the following is a specification, reference being had to the accompanying drawing, forming part thereof.

Fig. 1 is a side elevation of the airplane toy, showing my new design;

Fig. 2 is a top plan view thereof.

I claim:

The ornamental design for an airplane toy, as shown.

ANDREW HALVAS.
